Primary Examiner — Darlington Ly*Assistant Examiner* — Giang Hoang Tran(57) **CLAIM**

The ornamental design for a bicycle as shown and described.

DESCRIPTION

1.1 is a right side elevation view of a bicycle embodying my new design;

1.2 is a top, front and left side perspective view thereof; and

1.3 is a top, rear and right side perspective view thereof.

The present design relates to a bicycle; Dashed lines refer to optional features of the design, which do not limit the scope for which protection is claimed.
